INVENTOR.

William H. Vidor,
BY
Fraunzef and Richards,
ATTORNEYS.

UNITED STATES PATENT OFFICE.

WILLIAM H. VIDOR, OF MAPLEWOOD, NEW JERSEY, ASSIGNOR TO GLORIA MANUFACTURING CORP., OF NEWARK, NEW JERSEY, A CORPORATION OF NEW JERSEY.

LOUD SPEAKER.

Application filed June 25, 1925. Serial No. 39,448.

This invention relates to devices adapted to be actuated magnetically or mechanically to produce amplified sound waves, such devices being commonly known as loud speakers.

The invention has for its principal object to provide an apparatus whereby transmitted sound is reproduced in amplified volume, and with a high degree of resonance and clarity; and to this end the invention consists in providing a novel construction of vibratable diaphragm or resonator, with means for actuating the same, and a suitable support therefor.

Other objects of this invention, not at this time more particularly enumerated, will be clearly understood from the following detailed description of the same.

The objects of this invention are achieved by the novel design, construction and combination of parts hereinafter described and illustrated in the accompanying drawings, forming a material part of this disclosure, and in which:—

Figure 1 is a front elevation of a complete embodiment of this invention as arranged for operation.

Figure 2 is a vertical sectional view of the same taken on line 2—2 in Figure 1.

Similar characters of reference are employed in said above described views, to indicate corresponding parts.

The novel diaphragm or resonator, with the means for actuating the same, is provided with a suitable support. This support may be made in various styles, designs or shapes. One satisfactory design and shape of support is shown in the drawings, the same comprising a base 10 from which project upwardly oppositely directed outwardly bowed arms 11, the upper ends of which terminate in a head-piece 12, vertically spaced above said base. Said head-piece 12 is provided in its under side with a chamber 13.

Secured within the chamber 13 is a balanced telephone receiving unit, generally designated by the reference character 14, which is adapted to receive electrical impulses, produced by the sound waves to be transmitted in the usual manner, whereby a vibrator arm or element 15 with which the same is equipped is actuated.

Secured to said vibrator arm or element 15

is a downwardly extending rod 16 to which is attached a collar 17 adjustably held by a set-screw 18, or otherwise securely fastened to said rod. Suitably connected at its apex with said collar 17 is an outwardly flaring conical or bell-shaped diaphragm or resonator 19. The lower annular end of said diaphragm or resonator 19 has connected to it a reversed or inverted truncated conical element 20 providing an opening or mouth at its lower portion. Secured to the marginal portions of said opening or mouth is a rigid ring-member 21, which may be made of any suitable material, such as wood, metal, etc. Said ring-member 21 serves both to stiffen and reenforce the element 20, and at the same time, by its weight, provide the diaphragm or resonator with sufficient inertia to assure a proper reaction of the same to the vibrations imparted thereto by transmission from the vibrator arm or element 15 of the receiving unit 14 through the rod 16, whereby the desired reproduction of sound waves in amplified volume and resonance is effected by said diaphragm or resonator.

The elements 19 and 20, comprising the diaphragm or resonator, are preferably made from parchment, heavy paper, or some similar material, and are adapted to act as a sound box serving both to reproduce and amplify while at the same time clarifying the sound desired to be transmitted.

It has been determined by practical experiment that the sound produced by my novel device is not only greater in volume, but in clarity and resonance of tone is far superior to that hitherto attained by loud speakers of ordinary types of construction. I attribute the superior results obtained by my device, in the respects above mentioned, to the fact that the diaphragm or resonator possesses a minimum of initial stress (the inertia of the weight of the ring-member 21 being the main factor which provides the basis for the reaction of the diaphragm or resonator to imparted vibrations), and consequently my device is more sensitive, and is capable of responding more faithfully to the sound frequencies of music, speech or other sound forms.

As changes of construction could be made within the scope of the invention, it is intended that all matter contained in the fore-

going description or shown in the accompanying drawings shall be interpreted as illustrative and not in a limiting sense.

Having thus described my invention, I claim:—

- 5 1. A loud speaker comprising a support, a balanced telephone receiving unit affixed to said support, a vertical vibrating rod actuated by said unit, and a diaphragm means supported solely by said rod and adapted to be vibrated thereby, said diaphragm means consisting of two hollow conical elements connected at their base edges, the lower element being truncated and open at its center, the upper element being affixed at its apex to said rod.
- 10 2. A loud speaker comprising a support, a balanced telephone receiving unit affixed to said support, a vertical vibrating rod actuated by said unit, a diaphragm means supported solely by said rod and adapted to be vibrated thereby, said diaphragm means consisting of two hollow conical elements connected at their base edges, the lower element being truncated and open at its center, the upper element being affixed at its apex to said rod.
- 15 3. A loud speaker comprising a support, a balanced telephone receiving unit affixed to said support, a vertical vibrating rod actuated by said unit, a diaphragm means supported solely by said rod and adapted to be vibrated thereby, said diaphragm means consisting of two hollow conical elements connected at their base edges, the lower element being truncated and open at its center, and a weight ring connected with the open bottom end of said lower element, the upper element being affixed at its apex to said rod.
- 20 4. A loud speaker comprising a support, a balanced telephone receiving unit affixed to said support, a vertical vibrating rod actuated by said unit, a diaphragm means consisting of two hollow conical elements connected at their base edges, the lower element being truncated and open at its center, a weight ring connected with the bottom open end of said lower element, and means at the apex of said upper element for adjustably attaching said diaphragm means to said rod to both support and vibrate the same.
- 25 5. A loud speaker comprising a support, a hollow head on said support, a magnetic telephone receiver device secured within said head, a pendant hollow resonator means engaged with and operated by said telephone receiver device, said resonator means having an open lower free end, and a weight-ring connected with the lower open free end of said resonator means.

sisting of two hollow conical elements connected at their base edges, the lower element being truncated and open at its center, and means at the apex of said upper element for adjustably attaching said diaphragm means to said rod to both support and vibrate the same.

4. A loud speaker comprising a support, a balanced telephone receiving unit affixed to said support, a vertical vibrating rod actuated by said unit, a diaphragm means consisting of two hollow conical elements connected at their base edges, the lower element being truncated and open at its center, a weight ring connected with the bottom open end of said lower element, and means at the apex of said upper element for adjustably attaching said diaphragm means to said rod to both support and vibrate the same.

5. A loud speaker comprising a support, a hollow head on said support, a magnetic telephone receiver device secured within said head, a pendant hollow resonator means engaged with and operated by said telephone receiver device, said resonator means having an open lower free end, and a weight-ring connected with the lower open free end of said resonator means.

In testimony that I claim the invention as set forth above I have hereunto set my hand this 20th day of June, 1925.

WILLIAM H. VIDOR.
